UNITED STATES PATENT OFFICE.

GEORGE F. RAUCH, OF PUKWANA, SOUTH DAKOTA.

ELECTRIC SWITCH.

Application filed October 26, 1922. Serial No. 597,128.

To all whom it may concern:

Be it known that I, GEORGE F. RAUCH, a citizen of the United States, residing at Pukwana, in the county of Brule and State 5 of South Dakota, have invented certain new and useful Improvements in Electric Switches; and I do declare the following to be a full, clear, and exact description of the invention, such as will enable others skilled 10 in the art to which it appertains to make and use the same.

My invention relates to improvements in electric switches and the present disclosure is directed more particularly to a time 15 switch designed primarily for operating whistles or gongs in factories and the like to indicate the starting of work periods and the ending thereof. It will be understood, however, that the invention is not restricted 20 to this particular use.

The principal object of the invention is to provide a simple and inexpensive switch mechanism which can easily be operated by a clock mechanism. In carrying out this 25 end, a further object is to provide spring means for closing the switch after it has been initially started towards closed position by the clock mechanism. Similarly, another object is to provide for opening the 30 switch under the influence of a spring. By making these provisions, less power is required from the clock mechanism than would otherwise be necessary. The switch is normally set and yieldably held in open 35 position and a still further aim is to make novel provision for resetting the parts in fully open position, after the switch has been opened to some extent, by the spring means above referred to.

Yet another object is to provide a single actuating member carrying both a dog for starting the switch toward closed position and a resetting device for returning the switch to fully open position, after it is op- 40 erated.

The switch mechanism is adapted for closing an electric circuit, for instance, to operate a factory whistle at the proper intervals on week days, a further object of 45 the invention being to provide an additional switch for the same circuit, opened on Saturday night by the clock mechanism and held open until Monday morning, whereby the whistle or the like will not operate on 50 Sunday.

With the foregoing and minor objects in

view, the invention resides in the novel sub- 60 ject matter hereinafter described and claimed, the description being supplemented by the accompanying drawings.

Figs. 1, 2, 3 and 4 are elevational views showing different positions of parts.

Fig. 5 is a perspective view of the movable switch member.

Fig. 6 is a perspective of the actuator and 65 parts carried thereby.

Fig. 7 is a perspective of the switch closing spring.

In the drawings above briefly described, 70 the numeral 1 designates an appropriate support, preferably formed of insulating material in the form of a partition across a clock casing 2. Upon this support is mounted a clock mechanism 3 of any desired form, the sleeve 4 which commonly drives the hour hand of the clock being provided with a gear 5 which makes one complete revolution every twelve hours and meshes with a larger gear 6 mounted at one side of the support 1, for turning this gear once in every twenty- 75 four hours. The gear 6 is provided with a pinion 7 meshing with a third gear 8 which rotates once every seven days. The wheel 6 is provided with a plurality of tappets 9 for operating a switch for completing an 80 electric circuit several times during each day, while the gear 8 is provided with an arcuate cam 10 adapted to open another switch of the same circuit, every Saturday 85 night, as above referred to.

The day switch includes a movable mem- 90 ber 11 which is pivotally mounted on a bind- 95 ing post 12 extending through the support 1, said member 11 being normally out of en- gagement with a fixed contact 13 which also passes through the support. The switch member 11 is provided with a lateral arm 14 having an insulating pin 15 which is nor- mally engaged with a seat 16 of a head 17 carried by the upper end of a spring arm 100 18, whereby to yieldably hold the member 11 set at a fully open position, as indicated in Fig. 1. Below the seat 16, the head 17 is formed with an oblique cam 19. When the switch member 11 is initially started toward 105 closed position and the pin 15 is disengaged from the seat 16, the cam 19 acts upon said pin to quickly rock the said switch member to the completely closed position depicted in Fig. 3, thereby bridging the gap between the 110 binding post 12 and the contact 13 and completing an electric circuit.

For initially starting the switch member 11 towards closed position and for also assisting in resetting said switch member at its fully open position, I provide a movable actuator 20 which is preferably pivoted to the support 1 as indicated at 21. This actuator, in the form of construction herein disclosed, is provided with an inclined arm 22 to which a dog 23 is pivoted, said dog 10 being preferably formed in part of insulating material and having teeth 25 on its free end for engagement with a lateral projection 26 on the lower end of an operating arm 27 which depends from the switch 15 member 11. The actuator 20 is provided with a nose 28 disposed in the path of the tappets 9 and by reference to Fig. 3, it will be seen that engagement of any tappet with said nose will rock the actuator 20 upon its 20 pivot 21, thereby causing the dog 23 to engage the projection 26 and start the switch member 11 toward closed position. As soon as this movement takes place sufficiently to permit the cam 19 to act on the pin 15, 25 said cam completes the closing of the switch member 11 under the influence of the spring arm 18. Before the tappet 9 leaves the nose 28, however, the actuator 20 is further moved and I make use of this additional 30 movement for, first, tensioning spring means for opening the switch member, second, for releasing the tensioned spring means to permit it to open the switch member, and, third, for positively resetting said switch member 35 in completely opened position with the pin 15 engaged with the seat 16.

The spring means above referred to, preferably consists of a flat spring arm 29, suitably anchored at its upper end upon the 40 support 1, the lower end of said spring arm being preferably thickened by the addition of a suitable body of metal 30 thereto. A gravity-righted dog 31 is pivoted to the actuator 20 to engage the lower end of the 45 spring arm 29 during movement of said actuator to initially start the switch member 11 on its closing movement. This engagement obtains throughout the period during 50 which the switch member 11 is moving to completely closed position and for any desired time thereafter. When this time has 55 been reached, the dog 31 disengages from the lower end of the spring arm 29 and the latter in being thus released, snaps into contact with an insulating block 32 on the lower end of the arm 27, thereby quickly moving the switch member 11 from engagement with the contact 13. Still further movement of the actuator 20 now serves to 60 positively reset the switch member 11 in the position shown in Fig. 4.

In the preferred form of construction, the resetting device is in the form of a rod 33 pivoted at 34 to and rising from a substantially horizontal arm 35, extending

from the actuator 20, the upper end of said rod being received in a suitable guide 36 and being equipped with an insulated head 37 for contact with the lower side of the arm 14, after the switch member 11 has been 70 opened under the influence of the spring arm 29. Thus, the rod 33 will rock the switch member, causing its pin 15 to act against the cam 19 and retract the head 75 17, until said pin 15 is seated in the seat 16, as shown in Fig. 4. During this movement, a releasing arm 38 with which the dog 23 is provided, strikes a portion of the guide 36, or any other stationary part, so that said dog is rocked out of the path of the projection 26 of arm 27, thereby interfering in no manner with the opening movement of the switch member.

By the time the pin 15 is engaged with the seat 16, the tappet 9 which was previously turning the actuator 20 at a uniform speed, has disengaged from the nose 28 with the result that said actuator and the parts attached thereto return by gravity to the idle position disclosed in Fig. 1, at which position they are in readiness to be operated by the next tappet 9, so as to first close the switch member 11 and then open the same in the manner above described in detail.

While the switch mechanism above described may well be used separately from any other switch structure, I prefer that it be used in connection with a second switch controlled by the cam 10. This second 100 switch may well consist of a metal arm 40 pivoted to a binding post 41, extending through the support 1, said arm normally contacting with a contact pin 42 also extending through said support. One end of arm 40 is provided with an extension 43 suitably insulated therefrom and disposed in the path of the cam 10.

The switch of which the arm 40 forms a part, is included in the same circuit with 110 the time operated switch above described. It will thus be seen that regardless of any movement of the switch member 11, the circuit will not be completed if the arm 40 is held disengaged from the contact 42 by 115 means of the cam 10. Thus, while the switch member 11 will operate to complete the circuit, for instance, of a factory whistle at the required times during each day, the whistle or the like will not be operated on Sunday, 120 while the arm 40 is being held away from the contact 42 by the cam 10.

While any desired wiring may be used, I prefer to extend two line wires 44 and 45 through the casing 2, one of these wires being connected to the contact 13, while the other is anchored to the contact 42. Thus, by connecting the two binding posts 42 and 41 with a wire 46, the desired results will be obtained. It is, of course, understood that 130

the wires 44 and 45 are connected with the electric device to be operated and a source of electric current in any desired manner.

While I have not shown such an arrangement, it will be understood that a third switch might be operating from the gear 6 for the purpose of sounding a curfew at any desired time.

From the foregoing, taken in connection with the accompanying drawings, it will be seen that I have provided a highly efficient and desirable association of parts for carrying out the objects of the invention. Excellent results have been obtained from the general structure shown and described and it may therefore be followed if desired. It is to be understood, however, that within the scope of the invention as claimed, numerous minor changes may be made. For instance, the seven-day wheel 8 need not necessarily be located at the point shown on the drawings, but may be disposed at some other point if found more desirable.

I claim:

1. In combination, a movable switch member, a movable actuator having means for moving said switch member to closed position when said actuator is moved in one direction to a predetermined extent, means operated by said actuator for moving said switch member to open position, when said actuator moves further in the same direction, and chronometric means for moving said actuator in the specified manner.

2. In combination, a movable switch member, a movable actuator having a releasable dog for engaging said switch member and moving it toward closed position, means for releasing said dog after starting of said switch member, and means for quickly completing the closing movement of the switch.

3. In combination, a movable switch member, a movable actuator having a pivoted dog to engage said switch member and move the same toward closed position, said dog having a lateral arm, a stop in the path of said arm for releasing said dog when the switch member has been moved to a predetermined extent, and means for rapidly completing the closing movement of said switch member.

4. In combination, a movable switch member, a spring pressed holding device engaging said switch member and normally holding the same in open position, and means for starting said switch member toward closed position, said spring pressed holding device having a cam surface for engaging said switch member after starting thereof to rapidly complete its closing movement.

5. In combination, a movable switch member normally set at open position, a movable actuator for effecting closing of said switch member, a resetting device for said switch member carried by said actuator and

active after closing of the switch, and means for moving said actuator in the same direction until both closing and opening of the switch have been effected.

6. In combination, a movable switch member normally set at open position, a movable actuator for effecting closing of said switch member, a rod pivoted to said actuator to engage said switch member and reset the same at open position after closing thereof, and means for moving said actuator in the same direction until both closing and opening of the switch have been effected.

7. In combination, a movable switch member normally set in open position, a movable actuator for effecting closing of said switch member, normally inert spring means for opening said switch member, means for automatically tensioning said spring means by movement of said actuator in switch closing direction and for releasing said spring means upon further movement of said actuator, whereby to open the switch, and means operated by said actuator for positively resetting the aforesaid switch member after opening thereof.

8. In combination, a movable switch member, a movable actuator for effecting closing of said switch member, and a normally inert spring arm for opening said switch member when tensioned and released, said actuator having a dog for tensioning said spring arm and for releasing the same after closing of the switch.

9. In combination, a pivoted switch member, means for normally holding said switch member open and for completing the closing movement thereof when initially started, a pivoted actuator having a releasable dog for engaging said switch member and starting the same toward closed position, means for releasing said dog, normally inert spring means for opening said switch member when tensioned and released, said actuator having a dog for tensioning said spring means and for releasing the same, after closing of the switch, and a resetting device carried by said actuator for positively engaging said switch member with said first named means after opening of said member.

10. A time controlled circuit closer, including a switch member movable to open or close a circuit, actuating means for the member having a movable element provided with a plurality of actuators adapted for a cycle of operation to move the switch member to closed and open positions in a short interval of time, and chronometrically operated means for moving the element to produce a cycle of operation of the actuators.

11. A time controlled circuit closer, including a switch member movable to open or close a circuit, actuating means having a movable element provided with a plural-

ity of independent successively operating actuators movable through a cycle of operation for moving the switch member to closed and open position in a relatively 5 short interval of time, and chronometrically operated means for effecting a cycle of operation of the actuators.

12. A time controlled circuit closer, including a switch member movable to open 10 or close a circuit, means operable on said switch member for holding it in either open or closed position, actuating means for the switch member to move it to closed and open position in a relatively short period of time, 15 and chronometrically operated means for operating the actuating means.

13. A time controlled circuit closer, including a switch member movable to open

or close a circuit, actuating means for the member operable through a cycle of operation in a relatively short period of time for moving the member to closed and open position, auxiliary switch member operating means controlled by the actuating means operable for producing a quick break in the 20 circuit during the movement of the switch member to open position, and chronometrically operated means for operating the actuating means said actuating means for the switch member being interposed between 25 said switch member and the chronometrically operated means.

In testimony whereof I have hereunto affixed my signature.

GEORGE F. RAUCH.
